RICHARD C. MEISTERKNECHT, OF ALLENTOWN, PENNSYLVANIA.

CLOTHESLINE-PULLEY.

1,330,645.

Specification of Letters Patent.

Patented Feb. 10, 1920.

Application filed March 6, 1919. Serial No. 280,891.

To all whom it may concern:

Be it known that I, RICHARD C. MEISTERKNECHT, a citizen of the United States, and a resident of Allentown, in the county of 5 Lehigh and State of Pennsylvania, have invented a new and Improved Clothesline-Pulley, of which the following is a full, clear, and exact description.

This invention relates to pulleys or block 10 and tackle and has particular reference to means for locking or holding clotheslines or the like.

Among the objects of the invention is to 15 provide a pulley and shackle of peculiar construction providing for the practical automatic locking or unlocking of a clothesline or other rope.

Another object of the invention is to provide a self-holding pulley for an endless 20 clothesline, the same being so designed and constructed as to afford free traversing of the rope or line over the pulley when clothes are to be applied to or removed from the line, but which when it is to be held stationary will lock the pulley from movement 25 over the pulley by a member brought into gripping action automatically with the turning of the pulley around the axis of the line about 180 degrees.

30 With the foregoing and other objects in view the invention consists in the arrangement and combination of parts herein-after described and claimed, and while the invention is not restricted to the exact details of construction disclosed or suggested herein, still for the purpose of illustrating a practical embodiment thereof reference is had to the accompanying drawings, in which like reference characters designate the 35 same parts in the several views and in which—

Figure 1 is a perspective view indicating my improved pulley and shackle and having an endless rope or line arranged over 40 the pulley and held in locked position.

Fig. 2 is a horizontal section substantially on the line 2—2 of Fig. 1; and

Fig. 3 is a vertical longitudinal section on the line 3—3 of Fig. 2, but with the locking member dropped into idle position.

Referring now more specifically to the drawings I show my improvement as comprising a pulley casing or shackle 10 having a bail or loop 11 at one end typifying any 55 suitable means for attaching the shackle to a support and providing for rotation of the

shackle around a longitudinal axis. The shackle has the major part of its weight located on one side of its longitudinal axis so as to be normally held in an upright position under the action of gravity. In the other end of the shackle is journaled an elliptical pulley 12 having a groove 13 for a rope or line 14. This pulley is journaled upon a pin or bolt 15 fixed in the two side 60 wings of the shackle in any suitable manner.

16 is a locking dog held on a pivot or bolt 17 in or between the side walls of the shackle and below or at one side of the longitudinal axis of the shackle. Under normal conditions or when the pulley is rolling around its pivot pin 15 the dog 16 will assume the position of Fig. 3 where it is dropped well out of the path of the pulley, but with a lateral extension or lug 18 bearing 70 against a shoulder 19 whereby the swing of the dog is limited to less than a right angle from its locking position.

In the operation of this device and with the parts in the position shown in Fig. 3 a 80 rope or line mounted on the pulley will be free to be drawn in either direction or in other words the pulley will be free to roll in any direction around its pivot 15. If now the shackle and pulley be turned half way 85 around the longitudinal axis or namely the axis of the anchor rope or connection 20 bringing the dog at the upper side of the casing, it will drop promptly by gravity bringing the eccentric gripping face 21 of 90 the dog directly against the line as in Figs. 1 and 2. The friction applied to the line at this time will hold the dog in gripping position irrespective of the position of the shackle with respect to the aforesaid longitudinal axis. The normal position of the shackle or the position in which it normally tends to swing is that shown in Fig. 3, by reason of the fact that the dog and adjacent parts have sufficient weight to cause the device to assume this position. In order to 100 loosen the dog or release its grip upon the rope the operator, no matter how far remote he may be stationed from the pulley, has but to draw slightly upon the under run of 105 the line whereby the dog will drop to its idle position leaving the rope free again for rolling action over the pulley.

The point 21' of the dog or the longest portion of the eccentric face thereof extends 110 far enough from the axis of the pin 17 to strike against the face of the pulley thereby

insuring that the dog can never turn too far around said pivot pin 17. In other words the extended point 21' of the dog will prevent such point from passing the line drawn between the centers of the two pivots 15 and 17, but the dog will pass the downwardly projecting end of the pulley or that portion having a longer axis. Consequently the draft upon the upper run of the line will 10 cause the pulley to act in the nature of a lever of the first class having its fulcrum at 15 and the load or resistance at the lower end against the face 21 of the dog. The shoulders 19 are practically square so that 15 when the projection 18 strikes against them there is no binding action which might otherwise serve to prevent the free dropping of the dog into gripping position when the pulley is turned around the longitudinal 20 axis of the anchorage. The side portions of the shackle are preferably extended upward at 22 adjacent to the pulley to keep the line guided upon the face of the pulley 19 with no unnecessary weight on the upper side of 25 the shackle. This clothes line pulley may be made relatively cheap and yet be strong and durable as well as effective in practice and is practically indestructible, and if made of

non-corrodible metal or of any strong metal nickel plated or galvanized, will always be 30 clean and so will not contaminate the clothes line by rust or the like.

I claim:

1. In a clothesline fastener, the combination of a shackle, an elliptical pulley journaled in one end of the shackle, anchorage means at the other end of the shackle, the shackle being weighted below the line connecting the pulley and the anchorage means, and a gravity acting locking dog over the 40 pulley pivoted in the weighted side of the shackle arranged to lock the clothesline between one end of the elliptical pulley and said dog.

2. In a device of the class set forth, the 45 combination of a frame, an elliptical pulley journaled therein, and a gravity operated locking dog journaled in the frame and co-operating with the pulley in one position to prevent its rotation, there being provided 50 co-operating lugs and shoulders between the dog and the frame to limit the swing of the dog away from the pulley to less than a right angle, substantially as and for the purpose set forth.

RICHARD C. MEISTERKNECHT.
